UNITED STATES PATENT OFFICE.

LAWRENCE G. MCKAM, OF DETROIT, MICHIGAN.

RAILWAY-CROSSING.

1,289,499.

Specification of Letters Patent.

Patented Dec. 31, 1918.

Application filed February 21, 1918. Serial No. 218,417.

To all whom it may concern:

Be it known that I, LAWRENCE G. MCKAM, a citizen of the United States, residing at Detroit, in the county of Wayne and State 5 of Michigan, have invented a new and useful Improvement in Railway-Crossings, of which the following is a specification.

This invention relates to railway crossings and has for its object a crossing which 10 is easily assembled and which has great durability.

The crossing is so constructed that the treads of the wheels are lifted upon the flanges so that they do not drop into the usual groove in crossing a track, wearing 15 the ends of the rails that obtain at the groove and resulting in annoying and noisy jolts. The particulars of the construction will more fully appear hereinafter.

20 In the drawings,—

Figure 1 is a perspective view of a crossing embodying my invention.

Fig. 2 is a perspective view of the chair and the connecting rails showing how they 25 are assembled.

Fig. 3 is a longitudinal sectional view of a connecting rail and a pair of chairs.

Fig. 4 is a plan view of a chair with a connecting rail.

30 In an ordinary single crossing four chairs *a* are employed. Each chair is a casting having a head forming two fish plate-like flanges *b*, *b* to receive the ends of the connecting rails *c*. These flanges form the 35 socket of a scarf joint and the ends of the connecting rails *c*, *c* are formed into a notch and shoulder extension so that the connecting rails may be scarfed into the chair. Bolts may be passed through the bolt holes 40 in the flanges *b* and through the ends of the connecting rails to securely hold the connecting rails to the chairs and the connecting rails and chairs can all be held down to the track bed by spikes passing into ties 45 (not shown).

Obviously this affords a simple arrangement as the chairs are simply castings and can be made of manganese steel, which is 50 relatively hard and durable. This construction is made possible by the elimination of the necessity of hardened inserts by reason of the arrangement presently to be described. The connecting rails *c* not only are easy to assemble but when they are assembled in place it will readily be understood that by reason of the hook-like ends

of the scarf joint the rails not only serve as spacers but as ties to prevent the separating of the rails under the stresses that are delivered upon the crossing. 60

Each chair is provided with a pair of tails which comprise a rail section *d* and a fish-plate section *e*. The main rail which continues the track from the crossing may have its end abut against the end of the 65 rail section *d* and consequently will be overlapped near its end by the fish-plate section *e* so that bolts may be passed through the fish-plate section and the rail to bolt the rail to the chair in the customary way 70 of making a fish-plate joint.

Now referring to Fig. 2, it will be seen that the flange groove formed in the tail piece between the rail sections and the fish-plate section is inclined from the rear to 75 the head of the chair where the connecting rail ends abut against the chair. Consequently by this rise the flange comes in contact with the bottom of the groove and the tread of the wheel is thereby lifted about 80 $\frac{3}{16}$ ths of an inch above the rail so that the wheel rides noiselessly over the flange groove of the intersecting railroad track. The connecting rail *c* is preferably arranged with a flange groove with a high bottom so that 85 the wheel rides on the flange all the way across the connecting rail. Hence there is only one rise and fall at a crossing.

It will be obvious that in the case of a crossing with more than one track, the same 90 construction slightly modified may be utilized. The shape of the chair will be slightly different, some of the chairs having three or four scarf sockets and only one or no tail piece, depending upon the location of 95 the chair and the lay of the crossing.

What I claim is:

1. In a railroad crossing, a chair provided with a pair of fish plate-like flanges forming a socket and connected by a member whose 100 inside surface forms a shoulder, and a rail which can be assembled into the chair by dropping the same thereinto and which is provided with a notch and shoulder extension, the latter of which drops in behind 105 the shoulder formed by the connecting member and the former of which straddles the connecting member to form a scarf joint, substantially as described.

2. A railroad crossing having a chair por- 110 tion which comprises a rail section and a fish plate section, and a rail whose end may

be caused to abut against the end of the rail section of the chair and whose side will be overlapped near the end of the rail by the said fish plate section of the chair, and means 5 for holding the fish plate section and rail together.

3. In a railway crossing, a chair provided with one or more pairs of fish plate-like flanges forming each a socket with a notch 10 and a shoulder, and one or more connecting rails having at its end a scarf-like joint portion in the form of a notch and a shoulder, the end of the connecting rail adapted to be dropped in between the fish plate-like 15 flanges with the shoulder on the end of the rail engaging in the notch of the chair and the shoulder in the chair engaging in the notch in the rail, substantially as described.

4. In a railway crossing, a chair in the 20 form of a casting provided with one or more pairs of fish plate-like flanges forming sockets of a scarf joint, and one or more tails comprising each a rail section and a fish-plate section, and one or more connecting rails having a scarf-like end portion 25 adapted to be scarfed into the sockets of the chair.

5. In a railway crossing, a chair having

a head with one or more scarf joint sockets 30 and having one or more tail pieces with flange grooves gradually inclined from the rear toward the head for the purpose of lifting the flange and causing the tread of the wheel to clear the tread of the rail, and one or more connecting rails having ends 35 that can be scarfed into the scarf sockets of the chair.

6. In a railway crossing, a plurality of chairs having those portions which lie at the outside of the crossing provided with 40 flange grooves which are inclined gradually from the outside toward the inside of the chair for the purpose of lifting the flange and causing the tread of the wheel to clear the tread of the rail.

7. In a railway crossing, the combination 45 of a plurality of chairs provided with intersecting flange grooves which have the flange groove bottom inclined from the outside to the inside of the chair for the purpose of lifting the tread of the wheel over the intersecting flange groove by reason of the wheel riding on the flange.

In witness whereof I have hereunto set my hand on the 15th day of February, 1918. 55

LAWRENCE G. MCKAM.
